UNITED STATES PATENT OFFICE.

AGLIBERT PILLET, OF BUENOS AIRES, ARGENTINA.

HAME FOR DRAFT HORSES OR MULES.

Application filed August 20, 1924. Serial No. 733,212.

This invention relates to improvements in hames for draft horses or mules.

As is well known, heretofore it has been usual to construct hames from solid iron, 5 hollow iron, or from wood, but these constructions employed up to the present have not been satisfactory as in most cases they do not offer sufficient resistance in service or they are inconvenient owing to their excessive weight.

The present invention has for its object to provide an improved type of hames being of comparatively low weight but sufficiently 15 resistant to resist tear and wear during service.

Amongst other types, it has been usual to construct hames from wood, reinforcing this construction by means of a metal plate disposed at its outer surface. However, 20 practice has shown that this construction does not offer a desirable resistance, as in this way the parts which are principally subject to tear and wear remain unprotected.

According to the present invention, the 25 improved hame is constructed from wood in the usual manner and reinforced by means of a metallic plate of substantial angular cross-section thereby providing an efficient protection to all those parts subject to strain 30 during service.

My invention is illustrated in the accompanying drawing which shows a preferred form of embodiment thereof,

In this drawing, which illustrates a perspective view of the improved hame, 1 is 35 the wooden part thereof provided with the reinforcing member of substantial angular cross-section 2 secured to the wooden part 1 by means of the rivets, or the like, 3. The reinforcing member 2 is provided with slots 40 4, corresponding with the slots in the wooden part 1, which serve for securing together both hame members, by means of a belt or the like, when assembled for use, and also with perforations to accommodate the usual 45 bolts, or the like, for securing the common rings 5 and hook 6.

Although the reinforcement member 2 in the present form is shown as being of substantial right-angled cross-section, I do not 50 desire to limit my invention to the use of this particular section, as any other adequate angular cross-section may be used, as for instance:—T, U, or V shape.

I claim:—

The combination in hames for draft animals, of a wooden member constituting the support for the usual connecting rings and hooks with a metallic reinforcement of substantially right angled cross-section one face 60 of which is disposed on that portion of the hame which is to the rear with regard to the line of draft and the other face disposed on the outer face of the hame adjacent thereto.

In testimony whereof I affix my signature.

AGLIBERT PILLET,
